SKATE FOR ROLLER SKATING

Alan E. Murray, New York, N. Y.

Application August 12, 1946, Serial No. 690,050

12 Claims. (Cl. 280—11.28)

1

My invention relates particularly to skates adapted for roller skating of all kinds.

The object of my invention is to provide roller skates, by means of which a far more effective mechanism for supporting the foot or body of the skater from the rollers is available. Another object is to provide roller skates, by means of which the impedance to the momentum of the wearer of the skates, due to minute or other unevennesses in the floor, is substantially entirely eliminated. Another object of my invention is to provide roller skates in which the body of the skater is suspended by means of elastic tension from the rollers of the skates. A further object is to provide such elastic tension while preventing metal contacts between the parts of the skate mechanism. An underslung suspension is preferably provided for this purpose. Another purpose is to provide a construction in which the parts tend to become self-aligning. Another object is to provide a chassis construction for the skate which can be partly built and completed by the wearer to suit the most desirable conditions for the individual skater. For instance, the elastic suspension may be applied or renewed by the wearer to provide the desired degree of tension or resistance to movement desired by the wearer of the skates and the plates used for attachment of the skate platform to the roller mechanism may be placed at will, and so as to vary, as desired, the angles to the vertical of the axes on which the two pairs of rollers, with their struts, axles and axle housings, rotate in the turning movement of the skate while skating. Further objects of my invention will be seen from the detailed description hereinafter.

While my invention is capable of embodiment in many different forms, for the purpose of illustration I have shown only certain forms thereof hereinafter, in the accompanying drawings, in which:

Fig. 1 is a side elevation, partly in section, of a roller skate made in accordance with my invention;

Fig. 2 is a vertical cross-section of the same;

Fig. 3 is a horizontal section of one of the axle housings showing the mounting of the rollers thereon;

Fig. 4 is a plan view of one of the axle housings, showing the lower elastic suspension of the body of the skate therefrom;

Fig. 5 is an enlarged left side elevation showing the upper elastic connection of the body of the skate to the front axle housing;

Fig. 6 is a rear elevation of the same;

Fig. 7 is a side elevation similar to Fig. 5, but showing a modified form of elastic connection;

Fig. 8 is a side elevation of another form of suspension means that may be used instead of the embodiment in Fig. 1;

Fig. 9 is a side elevation of still another modified form of suspension means that may be used;

Fig. 10 is a plan view of the shoe-supporting plate shown in Fig. 9;

Fig. 11 is a side elevation of a shoe-supporting plate in a modified form of the plate shown in Fig. 9, to be used with an arched shoe;

Fig. 12 is a side elevation showing another modification of the suspension means shown in Fig. 1;

Fig. 13 is a plan view of a detail thereof;

Fig. 14 is a plan view of one of the hook plates that can be used in attaching the axle housings elastically to the shoe-supporting plate of the skate;

Fig. 15 is a rear elevation, partly in section, of a modified elastic suspension between the foot plate and the axle housings;

Fig. 16 is a front elevation of a front bracket of another form of suspension for the axle from the foot plate; and

Fig. 17 is a similar view, partly in section, showing the elastic cord windings thereon.

In the drawings, referring first to the form of my invention shown in Figs. 1 to 6, I have shown a shoe 1 of any desired character, having attached thereto a plate 2 of wood, in any desired way, as, for instance, by screws (not shown). The plate 2, if desired, may have on opposite sides thereof,

35 cut out curved recesses 3 and 4 to provide ample room for the turning direction of movement of two front rollers 5 and two rear rollers 6. To the bottom of the plate 2 there may be attached a strut in the form of a block 7, of wood or other material, by means of four screws 8. Said block 7 may, also, have on the opposite sides thereof curved recesses 9 and 10 to provide ample room in the turning directions of the rollers 5 and 6. Furthermore, the block 7 may have front and

40 rear extensions 11 and 12 thereon, through which a rod 13 extends longitudinally and having screw-threaded ends 14 thereon carrying tapered nuts 15, 16, 17 and 18.

The rod 13 is underslung beneath axle housings 19 and 20 having therein axles 21 and 22, to provide axial support for the rollers 5 and 6. As shown in Fig. 4, the axle housings 19 and 20 are then secured above the rod 13 by wrappings of a cord 23 of rubber or rubber substitute about 55 $\frac{1}{16}$ " in diameter under tension, or some stretch-

ing while being applied, between the tapered nuts 15 and 16, and between the nuts 17 and 18. If desired, however, some of the wrappings, preferably the inner ones, could be made with an artificial rubber and the others, preferably the outer ones, could be made with natural rubber cord. The rubber substitute is stiffer, more resistant, but less elastic than required, yet with adequate elasticity being obtained. The two series of wrappings are just alike and only one thereof will be described in detail, accordingly. Preferably one piece of the cord is used for all the wrappings around the axle 21 and the screw-threaded end of the rod 13. For this purpose there is first applied a spaced spiral wrapping 24 extending between the nuts 15 and 16 and then a similar or second wrapping 25 above one half of the first wrapping between the housing 19 and the nut 16, towards the middle of the skate. Then a third series of about three diagonal wrappings 26 are made around the axle housing 19 and the rod end 14, and then a fourth series of about three similar diagonal wrappings 27 at right angles to the wrappings 26. These wrappings 25 and 26 will pull the housing 19 and rod end 14 together. Then there are applied a fifth series of about five horizontal wrappings 28 to form a neck of the wrappings between the housing 19 and the rod end 14. This tends to pull down a hook 29, which forms a part of an axle hood including the housing 19. While I may use the hook 29 for this purpose, it is to be understood that any other eye member may be used instead of a hook wherever I have mentioned herein a hook. Then there are applied a sixth series of about three or four wrappings 30, each horizontally towards the front around the hook 29 (there being a corresponding oppositely supplied rear hook 31 on the housing 20 and then down behind and underneath each side of the axle housing 19 and again horizontally around the front of the hook 29 to make the said three or four wrappings, so as to pull the hook 29 upwardly somewhat to give it a direction, inclined towards the front for the front axle (and towards the rear for the rear axle), at an angle of about 10° to the vertical, or nearly vertical, for ordinary and fancy skating, but preferably at a still greater angle to the vertical for speed skating (see Fig. 5), although any other angles can be chosen. Thereupon I apply a seventh series of crossed diagonal windings, each of about ten diagonal wrappings 32, 33, and there may be alternated repetitions of these crossed diagonal windings indicated diagrammatically at 32, 33 until, around the crossed housing 19 and the rod 14, there are about six layers of these alternating crossed diagonal windings. Then there are applied an eighth set of figure-8 windings 34, 35, the figure-8 windings 34, about ten in number, being looped under the rod end 14 fore and aft and crossed above the housing 19, and the figure-8 windings 35, about ten in number, being looped under the axle housing 19 and crossed above the axle housing 19. Finally, there can be added on the outside a ninth set of alternating diagonal wrappings like the wrappings 32, 33, with more or less of the wrappings 32 or 33 in one direction, to make the distance between the right side rollers equal to the distance between the left side rollers.

It will be noted from Figs. 1, 5, 6 and 14, that the hook 29 is attached at the front and rear of the skate to a hook 35 secured to a plate 36 attached to the wooden plate 2 by screws 37 passing through slots 38 so that, if desired, by the

lateral adjustment of the plates 37 the four rollers 5 and 6 can be adjusted so as to occupy the same horizontal plane. The hook 29 can be secured to the hook 35 to suspend the latter, by further wrappings of a cord or cords of rubber or rubber substitute 39, or both, preferably a rubber substitute underneath and rubber outside. Also, as shown in Fig. 6, the hook 35, at the front or back of the skate, or both, will preferably be located to one side or the other, as desired, of the hook 29, before applying the wrappings thereto. Metal contact between the same is avoided by the position shown in Fig. 6, of the windings applied thereto. A first series of about three to five windings 40 is applied vertically around the two hooks 29 and 35 to bind them together. Then a second series of about five or six windings 41, which actually spread the hooks apart as in Fig. 6, is applied horizontally around the windings 40. Thereafter, a third series of windings 42, like the windings 40, is applied. Finally a fourth series of about twenty windings 43 is applied horizontally, like the windings 41. The windings 43, or the windings 41, or both, serve to separate the two hooks 29 and 35 to prevent metal to metal contact.

As shown in Fig. 7, a modified form of a double hook 44, in the place of the hook 35, can be used so as to have two laterally directed straddling hooks 45 and 46, which may be each attached to the hook 29 by similar wrappings to those applied to the hooks 29 and 35, as for instance alternating layers of, each, about five windings 47 and 48 going around the hook 29 and the hook 45, and around the hook 29 and the hook 46, respectively, as well as a series of about twenty horizontal windings 49 going between the hook 29 and the hooks 45 and 46 to separate the hooks. In this way, the straddling of the hook 29 by the hooks 45 and 46 provides a suspension by the latter from the hook 29.

As shown in Fig. 15, still another form of hook 50, which is arranged transversely of the foot, may be provided in the place of the hook 35. In this instance the hook 29 passes through the hook 50 and, if desired, the latter may, but not necessarily, have thereon a preliminary winding 51 of a rubber or rubber substitute cord. Also, this or another similar cord may be applied to bind the hooks 29 and 50 towards each other by providing, first, alternating layers of about ten each of crossed layers of windings 52 and 53, as shown in Fig. 15, each layer being arranged to go through both hooks 29 and 50 so that in use, when skating, the foot becomes suspended from the hooks 29 by the hooks 50.

Each of the axles 21 and 22, which are constructed alike, preferably has scorings 54 on the middle portion so as to firmly position them in their respective housings 19, 20. Besides, the ends of the axle are screw-threaded to receive thereon conical inner and outer ball races 55 and 56 to support series of bearing balls 57 and 58 so as to cooperate with roller races 59 and 60 on a sleeve 61 fastened in each roller 5 and 6. Outside the outer races 56 there is a D-shaped washer 62 cooperating with a flat area 63 on the underside of the axle 21, 22. Outside of the D-washer 62 there is a nut 64, to secure each of the rollers 5 and 6 from lateral displacement on its axle. If desired, there may be a fibre oil-guard 65 located between each inner ball race 55 and the adjacent part of the housing 19, 20. Also, if desired, there may be applied to the outside of each of the

rollers 5 and 6 a dust cap 66 by means of screws 67.

As illustrated in Fig. 8, I have shown another form of suspension means instead of the block 7. In this instance, instead, I have shown two cylindrical hollow metal standards or struts 68 and 68a, having circular plates 69 and 70 secured thereto, which are fastened by screws 71 to the wooden plate 2. These cylinders 68 and 68a are closed at the bottom by welded caps 72 and 73 and are provided with lower front and rear flat circular areas 74 through which the rod 13 passes, and is provided with long screw-threads 75 and 76 to receive tapered nuts 77 and 78, in addition to the tapered nuts 15, 16, 17 and 18 previously referred to.

A variation of the construction in Fig. 8 is shown in Figs. 9 and 10, in which the construction is the same as in Fig. 8 except that instead of the unitary rod 13 there are a longitudinally adjustable front rod 79 and a longitudinally adjustable rear rod 80. Also, in this instance there are welded to the inner ends of the rods 79 and 80, hooks 81 and 82 respectively, and around the two hooks, through the eyes thereof, there are a first layer of about ten horizontal windings 83 of said rubber or rubber substitute cord, and a second vertical layer 84 of about ten windings thereof, which prevent metal to metal contact and strongly return the rods 79 and 80 to their alignment from any variation thereof during skating, due to any flexibility in the shoe 1, made of leather or molded from rubber and fabric or rubber substitute and fabric materials. If desired, there may also be provided a similar attachment comprising hooks 79a and 80a attached to the standards 68 and 68a, said hooks having elastic cord windings 84a like the windings 84. In this form the flexibility movement is aided owing to the plate 2 being substituted by a two-part plate 85 and 86, between which there are two rubber or rubber substitute blocks or plates 87 and 88 attached, respectively, to the inner adjacent ends of the two-part plate 85 and 86. Said inner ends of the plates 85 and 86 are bound together by a rubber or rubber substitute cord 89, of the above character, which passes through holes 90 and 91 in the two plates 85 and 86, respectively.

In Fig. 11 I have shown another modified form of suspension which is similar to that just described in connection with Figs. 9 and 10. In Fig. 11, however, instead of the two-part plate 85 and 86 I may use a flexible platform 92 of laminated wood or laminated fabric and rubber or a rubber substitute, to which the standards 68 and 68a, for suspension of the foot, are attached, when wearing an arched shoe 93. In this instance the construction is more rigid than that shown in Figs. 9 and 10. Accordingly, there may be arranged higher up screw-threaded rings 94 and 95, secured to the supports 68 and 68a, respectively, to receive the screw-threaded ends of hooks 96 and 97, respectively. These hooks 96 and 97 may be bound together, yieldingly, by horizontal 98 and vertical 99 windings of the rubber or rubber substitute cord, which, as in all the other instances of windings therewith herein, the windings are applied preferably under some tension or stretching.

In Figs. 12 and 13 I have shown still another form of suspension. This is the same as in Fig. 1, except that I provide rods 100 and 101 which pass through and are fastened to front and rear struts or blocks 102 and 103 respectively by the tapered

nuts 16 and 17 on the outside of the blocks 102 and 103 and nuts 104 and 105 on the inside of said blocks. The blocks 102 and 103 are secured to front and rear wooden plates 106 and 107 by four U-shaped screw-threaded bolts 108, 109, 110 and 111 and nuts 111a. The blocks 102 and 103 have adjoining tapered inner ends 112 and 113, to provide more turning space to receive the rollers 5 and 6, which have four spherical recesses 114, 115, 116 and 117 to receive two rubber balls 118, 119 of any desired construction, but preferably having a core or body of rubber or an artificial rubber cord, as above referred to, wound under tension. To apply further compression to the balls 118 and 119 the blocks 102 may have therein eight screw hooks 120, 121, 122, 123, 124, 125, 126 and 127. These screws are bound together elastically in pairs 120 and 121, 122 and 123, 124 and 125, and 126 and 127, by means of any desired number of windings 128 of said rubber or an artificial rubber cord under tension.

In Figs. 16 and 17 I have shown a modified form of elastic suspension of the axle housing and the foot plate. In this instance there is provided a bracket 129 of metal having two depending arms 130 and 131 provided with holes in their ends through which a cylindrical rod 132 passes and is held tightly, or loosely for removability therein, as desired. This makes an opening 133 through which the upper end of the hook 29 can pass, although the hook can pass below the rod 132, if desired. Four screw holes 134 are provided in the plate 129 for attachment of the latter to the plate 2. The hook 29 is attached to the bracket 129 by suspension therefrom with an elastic cord of rubber or a rubber substitute, such as that above referred to. For this purpose a first winding 135 is made around the rod 132. Then a second winding 136, of about five turns, is made diagonally over and around the middle part of the hook 29 through the opening 133 and around the rod 132 near the arm 130. Then a third winding 137, of about five turns, is made similarly over and around the middle part of the hook 29 and thence through the opening 133 and around under the rod 132 near the arm 131. Then a fourth winding 138, of about five turns, is made like the second winding but extending around under the combined rod 132 and arm 130. Thereupon, a fifth winding 139, of about five turns, is made like the fourth winding but, instead, around under the combined rod 132 and arm 131.

In the operation of my invention, referring first to the form in Figs. 1 to 6, the skates, while skating, provide an extraordinary amount of elasticity and flexibility so as to override all unevennesses in the skating floor, without impeding the momentum of the skater due to the elastic suspension of the skater from the axle hoods or housings 19 and 20. This is particularly true due to the underslung position of the rod 13 which is suspended, without metal contacts, beneath the axle housings 19 and 20. Nevertheless, the windings of the rubber or rubber substitute cords which suspend the rod 13 from the housings 19 and 20 are such as to permit a very great angular turning movement while providing for returning the foot and skate always to its original normal position. This suspending action, with freedom from metal contacts, is also present due to the position of the hooks 35 and 29 so that the former becomes suspended from the latter but always returns to the normal position, nevertheless. It will be understood, also, that the cord 75 windings can be applied by the individual skater

to apply the degree of tension or resistance to movement or elasticity desired by him and that, furthermore, he may even supply his own elastic cords, axles and particular rollers carried thereon, so that he can make the final assembly thereof, as desired.

The same is true in the hook suspension in Fig. 7, wherein the hooks 45 and 46 become elastically suspended from the hook 29 in skating due to the elastic cord windings as placed thereon. This of itself gives an important elastic suspension irrespective of the form of the attachment of the axle housings 19 and 20 to the foot, especially as the shape of the hooks 45 and 46 always returns the hook 29 to the middle position between them.

In Fig. 8 the operation is substantially the same as in Figs. 1 to 6.

In Figs. 9 and 10, the operation is similar to that of Fig. 8, but in Figs. 9 and 10, however, there is still more freedom of action in skating due to the relative possible different rotations of the front roller 5 mountings from the rear roller 6 mountings, not only on vertical axes but also on horizontal axes due to the elastically bound rubber or rubber substitute plates 87 and 88 bound together with the rubber or the rubber substitute binding 89, but also due to the hooks 79 and 89 and their elastic bindings 84, which, however, always return the skate to normal position.

In Fig. 11 the operation is similar to that in Figs. 9 and 10, except that here there is a supporting laminated plate 92 for the arched shoe 93, which permits a torsional movement in said plate 92 on a horizontal axis and even some relative axial turning movement on said axis between the supports for the front rollers 5 and the rear rollers 6 owing to the elastic bindings 90 between the hooks 96 and 97.

In Figs. 12 and 13 the operation is similar to the action in Figs. 9 and 10. Here, however, the compression present in the balls 118 and 119 gives a greater resistance to displacement of the foot from the normal position of the struts 102 and 103 and a more positive return to the normal position of the skate. Also, a more free or ready adjustment of the relative positions of the supports for the front rollers 5 and the supports for the rear rollers 6 can be attained.

In Fig. 15 the suspension is similar to that shown in Figs. 5 and 6, but here the upper hook 50 is suspended from the lower hook 29, by the elastic windings 52 and 53, as each of the hooks 29 and 50 passes through the other.

In Figs. 16 and 17, another effective form of suspension of the foot from the lower hook 29 is provided in that the rod 132 is suspended therefrom by the elastic windings 136, 137, 138 and 139.

While I have described my invention above in detail I wish it to be understood that many changes may be made therein without departing from the spirit of the same.

I claim:

1. A roller skate device comprising a pair of rollers near each end of the skate, said skate having an axle support in the form of an axle housing carrying a hook, and a foot-supporting element having parts extending above and below the axle, an elastic cord connection from the upper part of said element to said axle housing hook and another elastic cord connection from said element to said axle, permitting horizontal rotary shifting of said axle, for allowing said

element to be suspended from the axle elastically, the elastic connection between the hook on the axle housing and the foot-supporting element being located at an angle to the vertical to permit horizontal guiding movement of the skate.

2. A roller skate device comprising a pair of rollers near each end of the skate, said skate having an axle support in the form of an axle housing carrying a hook, and a foot-supporting element having parts extending above and below the axle, an elastic cord connection from the upper part of said element to said axle housing hook and another elastic cord connection from said element to said axle, permitting horizontal rotary shifting of said axle, for allowing said element to be suspended from the axle elastically, the elastic connection between the hook on the axle housing and the foot-supporting element being located at an angle to the vertical to permit horizontal guiding movement of the skate and having a hook on said element to receive the elastic connection from the first mentioned hook.

3. A roller skate comprising a pair of rollers near each end of the skate, a roller support, including an axle, for a pair of the rollers, and a foot-supporting element having parts extending above and below the axle, elastic cord means rotatably yieldable horizontally for attaching the axle to the lower part of the foot-supporting element from below the axle elastically so as to exert a pull by extension from the axle and another elastic cord extending from the axle upwardly to the upper part of the foot-supporting element, permitting horizontal rotary shifting of said axle:

4. A roller skate comprising a pair of rollers near each end of the skate, a roller support including an axle for a pair of the rollers, a foot-supporting element having parts extending above and below said axle, including a connecting member above the axle, an elastic cord fastened to said connecting member, rotatably yieldable horizontally extending upwardly at an angle to the foot-supporting element above the axle, and another elastic suspension cord extending upwardly to the axle from the lower part of the foot-supporting element, permitting horizontal rotary shifting of said axle.

5. A roller skate comprising a pair of rollers near each end of the skate, a roller support including an axle for a pair of the rollers, a foot-supporting element having parts extending above and below said axle, including a depending eye member above the axle, an elastic cord fastened to said depending eye member, rotatably yieldable horizontally extending upwardly at an angle to the foot-supporting element above the axle, and another elastic suspension cord extending upwardly to the axle from the lower part of the foot-supporting element, permitting horizontal rotary shifting of said axle.

6. A roller skate comprising a pair of rollers near each end of the skate, a roller support including an axle for a pair of the rollers, a foot-supporting element having parts extending above and below said axles, including a depending eye member above the axle, an elastic cord fastened to said depending eye member rotatably yieldable horizontally extending upwardly at an angle to the foot-supporting element above the axle, and another elastic suspension cord extending upwardly to the axle from the lower part of the foot-supporting element, permitting horizontal rotary shifting of

said axle, the axle having a housing with another eye member to which the first mentioned elastic cord is attached.

7. A roller skate comprising a pair of rollers near each end of the skate, a roller support including an axle for each pair of rollers, a foot-supporting element having parts extending above and below said axles, including depending eye members above said axles, elastic cords fastened to said depending eye members, rotatably yieldable horizontally extending upwardly at an angle to the foot-supporting element above the axles, and additional elastic suspension cords extending upwardly to the axles from the lower parts of the foot-supporting element, permitting horizontal rotary shifting of said axles, said foot-supporting element having a depending standard extending downwardly between the pairs of rollers to which the second mentioned elastic cords are attached.

8. A roller skate comprising a pair of rollers near each end of the skate, a roller support including an axle for each pair of rollers, a foot-supporting element having parts extending above and below said axles, including depending eye members above said axles, including depending eye members above said axles, elastic cords fastened to said depending eye members, rotatably yieldable horizontally extending upwardly at an angle to the foot-supporting element above the axles, and additional elastic suspension cords extending upwardly to the axles from the lower parts of the foot-supporting elements, permitting horizontal rotary shifting of said axles, said foot-supporting element having two yieldably connected depending standards extending downwardly between the pairs of rollers to which the second mentioned elastic cords are attached respectively.

9. A roller skate comprising a pair of rollers near each end of the skate, a roller support including an axle for each pair of rollers, a foot-supporting element having parts extending above and below said axles, including depending eye members above said axles, elastic cords fastened to said depending eye members, rotatably yieldable horizontally extending upwardly at an angle to the foot-supporting element above the axles, and additional elastic suspension cords extending upwardly to the axles from the lower parts of the foot-supporting element, permitting horizontal rotary shifting of said axles, said foot-supporting element having two rigidly connected depending standards extending below the axles downwardly between the pairs of rollers to which the second mentioned elastic cords are attached respectively.

10. A roller skate comprising a pair of rollers near each end of the skate, a roller support including an axle for a pair of the rollers, a foot-supporting element having parts extending above

5 to the foot-supporting element above the axle, and another elastic suspension cord extending upwardly to the axle from the lower part of the foot-supporting element, permitting horizontal rotary shifting of said axle, and the axle having 10 an axle housing with an upwardly directed eye offset laterally from the first mentioned eye for connection thereto with the first mentioned elastic cord.

11. A roller skate comprising a pair of rollers near each end of the skate, a roller support including an axle for a pair of the rollers, a foot-supporting element having parts extending above and below said axle, including a depending eye member above the axle, an elastic cord fastened 15 to said depending eye member, rotatably yieldable horizontally extending upwardly at an angle to the foot-supporting element above the axle, and another elastic suspension cord extending upwardly to the axle from the lower part of the foot-supporting element, permitting horizontal rotary shifting of said axle, the depending eye member being mounted on a slotted shoe plate.

12. A roller skate comprising a pair of rollers near each end of the skate, a roller support including an axle for a pair of the rollers, a foot-supporting element having parts extending above and below said axle, including a depending hook member above the axle, an elastic cord fastened to said hook member, rotatably yieldable horizontally extending upwardly at an angle to the foot-supporting element from the axle, and another elastic suspension cord extending upwardly to the axle from the lower part of the foot-supporting element, permitting horizontal rotary shifting of said axle.
